(57) **CLAIM**

The ornamental design for an electrical socket assembly as shown and described.

DESCRIPTION

FIG. 1 is a right, front, top perspective view of an electrical socket assembly in an embodiment showing my new design; FIG. 2 is a left, rear, bottom perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a right, front, top perspective view of the electrical socket assembly with an open cover in FIG. 1; FIG. 10 is a left, front, bottom perspective view thereof; and, FIG. 11 is another left, front, bottom perspective view thereof.

In the drawings, the broken lines are for the purpose of illustrating portions of the electrical socket assembly that form no part of the claimed design.
